(57) CLAIM

An ornamental design for a watch case with charm holder, as shown and described.

DESCRIPTION

FIG. 1 is a front perspective view of a watch case showing my new design;

FIG. 2 is a left side elevational view thereof;

FIG. 3 is a right side elevational view thereof;

FIG. 4 is a top plan view thereof;

FIG. 5 is a back plan view thereof;

FIG. 6 is a bottom end elevational view thereof; and,

FIG. 7 is a top end elevational view thereof.

The broken-line showing in the FIGS. is for illustrative purposes only and forms no part of the claimed design.
